UNITED STATES PATENT OFFICE.

HARRY NORWOOD, OF BROOKLYN, NEW YORK.

DESIGN FOR A PORTABLE LAMP.

Application filed June 29, 1926. Serial No. 18,213. Term of patent 7 years.

To all whom it may concern:

Be it known that I, HARRY NORWOOD, a citizen of the United States of America, residing at Brooklyn, county of Kings, State of New York, have invented a new, original, and ornamental Design for a Portable Lamp, of which the following is a specification, reference being had to the accompanying drawings, forming part thereof.

Figure 1 is a side elevational view of a device embodying the new design;

Fig. 2, is a rear elevational view of a device, embodying the design;

Fig. 3, is a front elevational view of a device, embodying the design;

Fig. 4, is a bottom plan view of a device, embodying the design.

I claim:

The ornamental design for a portable lamp as shown.

In witness whereof I have signed this specification this 26th day of June, 1926.

HARRY NORWOOD.
